CLAIM

The ornamental design for an optical scanner, as shown in the accompanying drawings and described above.

DESCRIPTION

FIG. 1 is a top front perspective view of an optical scanner in accordance with the present invention.

FIG. 2 is a top rear perspective view of the optical scanner of FIG. 1.

FIG. 3 is a bottom rear perspective view of the optical scanner of FIG. 1.

FIG. 4 is a front elevation view of the optical scanner of FIG. 1.

FIG. 5 is a rear elevation view of the optical scanner of FIG. 1.

FIG. 6 is a right elevation view of the optical scanner of FIG. 1.

FIG. 7 is a left elevation view of the optical scanner of FIG. 1.

FIG. 8 is a top plan view of the optical scanner of FIG. 1; and,

FIG. 9 is a bottom plan view of the optical scanner of FIG. 1.

(Continued)

The broken lines depict unclaimed features of the optical scanner, shown for purposes of illustration, and forming no part of the claimed design.
